UNITED STATES PATENT OFFICE.

SALVATORE CASSISA, OF NEW YORK, N. Y.

DEEP-WELL PUMP.

1,390,085.

Specification of Letters Patent. Patented Sept. 6, 1921.

Application filed May 26, 1920. Serial No. 334,489.

To all whom it may concern:

Be it known that I, SALVATORE CASSISA, a subject of the King of Italy, and a resident of the city of New York, borough of 5 Manhattan, in the county and State of New York, have invented a new and Improved Deep-Well Pump, of which the following is a full, clear, and exact description.

10 This invention relates to pumping apparatus and particularly to a pump for pumping liquids from great depths or to great heights, and has for an object to provide an improved construction which will operate 15 in an efficient manner when raising liquids great distances.

Another object of the invention is to provide a pumping apparatus in which the lifting medium is compressed air with the parts 20 so arranged that a comparatively low pressure and large volume will operate to lift liquid to any desired height from a low altitude to a high altitude.

A further object more specifically is the 25 provision of a pumping outfit which uses air as the lifting medium, wherein pumps are arranged in such order that each pump will add a certain pressure to the air as it passes to the lifting part of the device while 30 the respective pumps utilize a comparatively small amount of energy.

In the accompanying drawings—

Figure 1 is a sectional view with certain parts in elevation showing a pumping apparatus embodying the invention and applied 35 to a well.

Fig. 2 is a diagram showing certain valve mechanism embodying certain features of the invention.

40 Fig. 3 is a detail fragmentary sectional view through Fig. 1 on the line 3—3.

Referring to the accompanying drawings by numerals, 1 indicates a storage tank which is provided with a gage 2 with a relief 45 valve 3. This tank is provided with an outlet pipe 4 having a manually actuated valve therein and a check valve 6 which will permit the air to flow freely from the tank 1 into the auxiliary pump casing 7, but will 50 not permit any back pressure from said casing into the tank. A primer pump 8 is provided adjacent tank 1, which pump is formed with a casing 9 and is provided with a piston 10 operated by any suitable source of power. 55 Inlet valves 11 are arranged centrally of the casing 9, while outlet check valves 12

and 13 are provided near the ends of the casing whereby the entire structure is arranged as a double acting pump. It will be evident that any other suitable form of pump may 60 be substituted provided the same will produce the desired pressure in the tank 1. The auxiliary pump 14 is provided with a piston 15 operated by a piston rod 16, which rod is moved by any suitable power. The pump 65 14 does not draw the air from the atmosphere, but from pipe 4 so that at the beginning of the power stroke the pressure in the casing 7 will be approximately the same as in the tank 1. Preferably the pump 7 is of 70 the same power as pump 8 so that at the end of the power stroke of piston 15 the pressure leaving the casing 7 will be approximately twice the pressure in tank 1.

Pipes 17 and 18 are tapped into the casing 7 adjacent the opposite ends thereof so as to receive compressed air from said casing. These pipes are connected to a number of containers 19, 20, 21, 22 and 23 arranged in the well 24. It will be noted that the pipe 75 17 is connected with the upper part of containers 20 and 22, while pipe 18 is connected with the upper part of containers 19, 21 and 23. The container 23 is preferably larger than the other containers and is arranged at the bottom of the well 24 so that by the action of gravity the oil or other liquid in the well will automatically move past the ball valve 25 into the container so as to fill the same up to the water line 26. A tube 27 90 extends from the bottom of container 22 downwardly through the upper part of container 23 and to a position near the bottom of the container 23 where a suitable ball valve 28 is provided and arranged to freely 95 open when there is an upward pressure in the pipe 27, but to instantly close when there is a downward pressure. It is evident that other forms of valves may be substituted for valves 25 and 28, but for simplicity and ease 100 of operation these valves are believed to be preferable. The other containers, namely, 19, 20 and 21 are each provided with a tube 27 provided with a ball valve 28 while the tube 27' extending downwardly into container 19 is provided with a discharge pipe 105 29 which may lead to any convenient point.

By this construction and arrangement when the pump is idle oil will move into the container 23 under the action of gravity and 110 as soon as piston 15 moves upwardly air will begin to pass through the pipe 18 and enter

into the upper part of containers 19, 21 and 23. As this air increases in pressure the oil in these respective containers will be forced past the respective valves 28 into the pipe 27 and consequently into the respective containers 20 and 22, while the oil in the container 19 will be forced out of discharge pipe 29. When the piston 15 reverses its action the pressure in pipe 18 will suddenly cease and 10 in fact will be reduced to atmospheric pressure by means hereinafter fully described, whereupon there will be no appreciable pressure on top of the oil in the containers 19, 21 and 23. However pressure will increase 15 in pipe 17 and consequently in the containers 20 and 22 whereupon oil from these containers will be forced upwardly into the next higher containers which are in communication with pipe 18. When the piston again 20 reverses pipe 17 will exhaust to the atmosphere, while pipe 18 will again be supplied with air under pressure and the action thereof against the oil in containers 19, 21 and 23 will be repeated. This alternate action of 25 air in the respective containers will continue as long as piston 15 reciprocates.

It will be observed that the oil at the bottom of the well will have intermittent opportunity of freely flowing into container 30 23 under the action of gravity and that a comparatively low pressure will be required to elevate the oil even though the depth of the well may be several thousand feet.

Ordinarily it requires about one atmosphere to raise oil thirty-two feet, and consequently it will require approximately three atmospheres to raise oil one hundred feet. If sections of pipes 27 are two hundred feet in length or approximately nine 40 atmospheres will easily raise the oil or other liquid being elevated. If desired the air pressure applied to pipes 17 and 18 may be greater so that the proper volume of air for the respective containers may be more 45 quickly supplied or a quicker action of oil may be produced.

The invention is shown as arranged in an oil well, but it may be arranged in a mine shaft, or may be arranged on the surface and 50 not only used for elevating oil but may be used for elevating water from mines or for elevating any form of liquid to high altitudes.

Exhaust valve mechanism 30 and 31 are 55 provided for the casing 7 adjacent each end so as to exhaust the pipes 17 and 18 alternately so as to permit oil to flow in the container 23 and also the oil being elevated to more easily flow in the remaining containers.

60 In Figs. 2 and 3 this mechanism is shown more in detail and is intended to open the opposite ends of the casing 7 to the atmosphere at the end of each compression stroke of the piston 15. Any suitable form of 65 mechanism which will accomplish this re-

sult may be used, but one form has been illustrated which is capable of accomplishing this result.

The valve 31 is provided with a casing 32 having a rotary or oscillating valve member 33 positioned therein so that when in open position it will appear as shown in Fig. 1. By a quarter of a turn the valve will be closed. In order to turn the valve member 33 a valve operating rod 34 is connected to a cross head 35 which is also connected to the valve operating rod 36. Pivotally connected on rod 34 are rack bars 37 and 38, bar 37 having a rack 39 adapted to rotate the ratchet wheel 40 for a quarter of a turn in one direction as the piston 15 moves upwardly. A wheel 40 is rigidly secured to the valve member 33 so that when the wheel is turned a quarter of a revolution the valve 31 will be closed. When the rack 39 moves downwardly on the return stroke it will slide freely over the ratchet wheel 40 but will not operate the same. The rack bar 34 is provided with a rack 41 which operates on the down stroke for opening the valve 31 as piston 15 completes its down stroke. The rack 41 will slide freely over the ratchet wheel 40 as it moves upwardly so that the valve 31 is open at the right time and left open until the rack 39 closes the 95 same, which is set to take place at approximately the instant the piston 15 reaches the pipe 4. As the valve 31 is closed during the rest of the upward movement of the piston the air may freely flow from tank 1 into 100 lower part of the casing 7.

The valve mechanism 30, rod 36 and associated parts are identical with valve mechanism 31, rod 34 and associated parts and therefore will need no additional description, said valve however operating on the opposite end of the casing 7. This form of valve mechanism has been illustrated merely to show an operative construction, but it will be understood that any desired 110 form may be used provided it accomplishes the same result.

I claim:

1. A pump for deep wells comprising a tank, a pump for supplying compressed air 115 to said tank, a second pump for receiving compressed air from the tank and compressing the same on each movement of the piston, a pipe connected to the opposite ends of said second pump so as to alternately receive compressed air therefrom, and direct it to a discharge point and means for alternately opening the ends of said last mentioned pump to the atmosphere.

2. In a multi-stage compressor a tank, a 120 pump for maintaining air under pressure in said tank, a second pump connected with said tank and adapted to receive air therefrom, a pair of discharge pipes associated with said second pump and adapted to re 130

- ceive compressed air from said second pump so as to direct the same to a discharge point, said second pump being provided with a piston and a piston rod for further compressing the air taken from said tank before it is discharged, out said pipes, and means for opening the opposite end of said second pump to the atmosphere, said last mentioned means comprising a valve mechanism at each end of said second pump, and means associated with the piston of the pump for alternately opening and closing said valves.
3. In a device of the character described the combination of a water elevator provided with a plurality of pipes, and means for using air alternately passing through said pipes, of a compressor for alternately forcing compressed air into said pipes, and 20 a valve co-acting with each of said pipes for opening the device to the atmosphere

and simultaneously opening the compressor to the atmosphere.

4. In a pump for deep wells means arranged in the well for causing water to flow 25 therefrom, air pipes for supplying air to said means, and means for supplying air to said pipes, said means including a valve for each pipe for opening the pipes to the atmosphere, a primary air pump, a tank for receiving air from said primary air pump, an auxiliary pump connected with said air pipes and with said tank whereby said auxiliary pump receives air from said tank and compresses the same to a higher degree immediately previous to the air discharged in said pipes, said auxiliary pump alternately exhausting simultaneously through the same valves that open said air pipes to the atmosphere.

SALVATORE CASSISA.
